BEER CAN PUNCH

Louis R. Manthey, Houston, Tex., assignor of
two-thirds to S. T. Jones and A. P. Brown, both
of Odessa, Tex.

Application April 7, 1953, Serial No. 347,311

2 Claims. (Cl. 30—6.1)

1

The present invention relates to certain new and useful structural and functional improvements in what may be conveniently referred to as a beer can punch, a type of a punch which is in the form of a hand tool or implement and which is so constructed that it serves to simultaneously punch two holes in the top of the beer can.

There are, of course, many and varied styles and forms of can punches and some which are constructed to punch two holes in the can at the same time. However, the can punch which is most commonly seen on the market and in use is one which fulcrums on and hooks over the one edge of the bead of a can which terminates in a substantially V-shaped punch with a pointed curving beak which penetrates the can in such a way as to form a substantially triangular pour hole. By way of contrast, the present tool is one which is characterized by a pair of substantially duplicate V-shaped punches which simultaneously function to punch two triangular pour holes through the can top.

More specifically, novelty is predicated on the dual or double triangular punch construction whose pointed vertices start punching and cutting from the inside portions of the top of the can and in a so-called sidewise manner which action serves to relieve air pressure equally from both sides of the can and prevents unduly disturbing the beer in the can, especially if it is not as cold as it should be for quick and reliable punching and opening requirements.

It is an obvious object of the invention to structurally, functionally, and otherwise improve upon beer can punches by providing one having the aforementioned structural characteristics and facilities and which includes in addition, a yoke which straddles the can and serves to provide diametrically opposite fulcrum-hooks, said hooks being releasably and conveniently engageable with the bead of the can in a manner to provide proper leverage for quick and easy can punching and opening results.

Other objects, features, and advantages will become more readily apparent from the following description and the accompanying sheet of illustrative drawings.

In the accompanying sheet of drawings where-in like numerals are employed to designate like parts through the views:

Figure 1 is an elevational view showing a fragmentary portion of a beer can or similar container and showing the improved punch and the manner in which the same is used;

2

Figure 2 is a view based on Figure 1 showing how the dual acting punches penetrate the can when the handle portion of the lever is pushed downwardly;

5 Figure 3 is a plan view, full size, of the improved beer can punch showing the particulars in the construction thereof;

10 Figure 4 is an end elevation observing the structure of Figure 2 in a direction from left to right; and,

Figure 5 is a top plan view showing the manner in which the holes, of usual triangular form, are punched in the top of a can.

In the drawings, the beer can is denoted by 15 the numeral 6 and it is conventional and includes a circular top 8 and a marginal bead 10. The diametrically opposite holes which are simultaneously formed in the top are denoted by the numerals 12 and 14.

20 The tool itself is a rigid one piece metal structural unit, one end of which is formed into a transversely curved rigid handle 16 having a hang-up hole 18. The left hand end portion of the handle is struck out to provide a bottle cap opener or lifting hook 20. At this same end there is a gradually widened portion which may be conveniently referred to as head. The portion 22 of the head is coplanar with the handle and the complementary half-portion 24 has a bend 26 whereby said portion 24 inclines at an approximate thirty degree angle to bring about the desired transmission of forces and the dependable leverage principles required. This portion 24 has a curvate edge 28, the center of which is denoted at 30. By reason of this formation it is convenient to refer to this obliquely bent half-portion 24 as a sort of a yoke. This yoke straddles the top of the can and at the ends of the curvate portion, that is on opposite 30 sides of the central point 30, can punches 32 and 34 are formed. These as shown in Figure 4 are substantially triangular and they have their pointed vertices, which may be described as beaks 35—35, angled and bent to properly penetrate and puncture the top of the can.

40 Disposed outwardly of the can punches are what may be called fulcrum-hooks and these are denoted by the numerals 36—36 having bill portions 38—38 positioned to properly engage the bead of the can in the manner shown in Figure 1. In this position, the yoke takes a position which is substantially perpendicular to the horizontal plane of the top of the can. The can punches 32 and 34 being at approximate 45 right angles to the plane of the yoke immedi-

ately take the correct positions so that a very slight down pressure on the handle serves to drive the pointed beaks 35 through the can to simultaneously punch holes and provide effective venting results. It follows that even if the beer in the can is slightly warm and the can is not as effectively and securely held as it should be, these two holes will vent the gases and prevent the beer from surging out in an often embarrassing and undesirable manner. The fact that the punches are located inwardly of the fulcrum-hooks and also located on opposite sides of the center point 30, brings about the desired allocation of elements and the resultant distribution of pressure and forces to insure the double puncturing step in an obvious manner. The provision of oblique angled yoke having anchor hooks which grip the bead of a can at diametrically opposite points with the yoke perpendicular to the horizontal plane of the can and the inwardly located triangular punches provides an aptly constructed, easily usable and reliable tool. It will be understood that the crown cap lifter 20 is an incidental feature but contributes to the over-all utility of the tool.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A beer can punch comprising a substantially straight rigid handle having an enlarged rigid head at one end of said handle, said head embodying a substantially flat segmental portion which is immediately adjacent to said one end and is substantially coplanar with the general plane of said handle, said head further embodying a complementary integral yoke, said yoke being adapted to span the end portions of

the stated beer can, said yoke having a substantially curvate crotch portion provided at its respective outer ends with a pair of hold-down and fulcruming hooks, said hooks being coplanar with each other and in the same plane with said yoke and having bill portions turned in toward each other, said yoke being oblique to the plane of said segmental portion and the edge defined by said curvate crotch being provided with companion can punches, said punches, being situated inwardly of the adjacent respective hooks.

2. A beer can punch comprising a substantially straight rigid handle having an enlarged rigid head at one end of said handle, said head embodying a substantially flat segmental portion which is immediately adjacent to said one end and is substantially coplanar with the general plane of said handle, said head further embodying a complementary integral yoke, said yoke being adapted to span the end portions of the stated beer can, said yoke having a substantially curvate crotch portion provided at its respective outer ends with a pair of hold-down and fulcruming hooks, said hooks being coplanar with each other and in the same plane with said yoke and having bill portions turned in toward each other, said yoke being oblique to the plane of said segmental portion and the edge defined by said curvate crotch being provided with companion can punches, said punches being situated inwardly of the adjacent respective hooks, said punches being substantially triangular in form, at right angles to the plane of said yoke, and situated at circumferentially spaced equidistant points on opposite sides of the center point of said curvate crotch.
